No. 37,007.

Patented June 28, 1904.

UNITED STATES PATENT OFFICE.

JAMES JOHN ALEXANDER MUNRO, OF TORONTO, CANADA.

DESIGN FOR A TABLE-KNIFE.

SPECIFICATION forming part of Design No. 37,007, dated June 28, 1904.

Application filed March 11, 1904. Serial No. 197,720. Term of patent 7 years.

To all whom it may concern:

Be it known that I, JAMES JOHN ALEXANDER MUNRO, a subject of the King of Great Britain, and a resident of Toronto, in the county of York and Province of Ontario, Canada, have invented a new, original, and ornamental Design for a Table-Knife, of which the following is a specification.

Figure 1 shows an elevation, and Fig. 2 a front view, of the table-knife of my design.

I claim—

The ornamental design for a table-knife, as shown.

JAMES JOHN ALEXANDER MUNRO.

Witnesses:

B. BOYD,
C. H. BAKER.
